(57) **CLAIM**

The ornamental design for a probe, as shown and described.

DESCRIPTION

FIG. 1 is a perspective view of a probe showing my new design;

FIG. 2 is a front view thereof, the rear view being a mirror image thereof;

FIG. 3 is a left side view thereof;

FIG. 4 is a right side view thereof;

FIG. 5 is a top plan view thereof; and,

FIG. 6 is a bottom plan view thereof.

The drawings include surface shading which represents contour and not surface ornamentation.

The parallel "dash-dot-dash" broken lines represent a symbolic break in the length of a portion of the probe and forms no part of the claimed design.
